UNITED STATES PATENT OFFICE

SEBASTIEN OTTO ALFRED FIEDLER, OF PARIS, FRANCE, ASSIGNOR TO L'AUXILIAIRE DES CHEMINS DE FER ET DE L'INDUSTRIE, OF PARIS, FRANCE

FEED WATER HEATER

Application filed August 2, 1929, Serial No. 383,080, and in France April 12, 1929.

The invention relates to feed water heaters and more particularly to the means for returning to the suction side of the water circulating pump, injector, or the like, which is adapted to supply the feed water heater with water to be heated, any excess of hot water which is not taken up by the pump or injector which is adapted to feed the boiler.

The invention has chiefly for its object to simplify the construction of the plant; another object is to provide improved means for returning said excess of hot water to the circulating pump or the like; a further object is to devise an arrangement which will efficiently prevent failing of the circulating pump or the like.

In my co-pending application No. 295,724, filed July 27, 1928, I have described an arrangement, wherein the excess of hot water is delivered into a receptacle open to the atmosphere, whence it is returned to the suction side of the pump or injector which supplies the mixing chamber, and said receptacle is located at a higher level than the suction vessel mounted on the admission pipe of the circulating pump.

It has been found that the plant may sometimes be simplified by dispensing with the receptacle open to the atmosphere and delivering directly the excess of hot water from the heater into the suction vessel of the suction pipe of the cold water pump, said suction vessel being now provided with a vent pipe.

These improvements are illustrated in the accompanying drawings, wherein:

Fig. 1 is a diagrammatic view showing a feed water heating plant according to the invention.

Fig. 2 is a cross-section of the pressure balanced valve shown diagrammatically in Fig. 1.

The feed water heating plant shown in Fig. 1 comprises a feed water heater embodying a mixing chamber 20 and a hot water distribution chamber 21, connected together by a water seal 25. Mixing chamber 20 has a heating steam inlet conduit 22 and a perforated tube 23 for the inlet of water to be heated. Water and steam are mixed together

and forced by steam pressure into chamber 21 through the water seal 25. Chambers 20 and 21 are substantially sealed, although they are provided with very small gas exhaust orifices 32, 33, and the water seal is so arranged that the weight of the water column therein is readily overcome by the steam pressure in chamber 20, whereby said joint is almost always blown off, chamber 20 being substantially constantly emptied of water.

Chamber 21 has several partitions forming weirs, whereby the gases dissolved in the water are readily disengaged and escape through orifice 33, through which the loss of steam is negligible. Orifice 32 is used similarly for the exit of the gases disengaged from the water in mixing chamber 20. The above-mentioned partitions bound a storage compartment 90 and an overflow compartment 29.

Into the bottom of the overflow compartment 29 of the distribution chamber 21 opens a hot water discharge tube 2 having at its lower part a small cylinder 4 in which is movable a piston valve 5 of suitable weight. On the side of said cylinder opens a pipe 6 affording communication between said cylinder and a suction vessel 70, open to the atmosphere through a vent pipe 80 of suitable height. At the upper part of cylinder 4 opens a tube 3^a connected with chamber 21 at a point situated above the maximum level of the water therein. Suction vessel 70 is connected by a pipe 71 with the source of cold water (not shown) and by a pipe 31 to the suction side of a pump 24 discharging through a pipe 5^a and tube 23 into chamber 20. The bottom of storage compartment 90 is connected by a pipe 26 to the suction side of a pump 27 forcing hot water into the boiler (not shown) through a pipe 100.

Piston valve 5 operates as follows: When water collects in compartment 29 of chamber 21, piston valve 5 is raised to allow the discharge of said water, under the pressure of the steam in chamber 21, into suction vessel 70. When discharge tube 2 is emptied of water, or nearly so, piston valve 5 is again lowered, thus preventing the escape of steam to the atmosphere.

Fig. 2 shows the details of construction of cylinder 4, whose openings 72, 73, 74 are respectively connected with pipes 3^a, 6 and 2. Piston valve 5 is slidably mounted in a mantle 77. A small draining orifice 63 (of 3 millimeters diameter for example) affords the exit of the condensate produced in pipe 3^a and whose weight would trouble the proper operation of valve 5. The loss of steam through said orifice is negligible.

It has been observed that, with a reduced pressure in chamber 21, impure water from pipe 71 leaks between valve 5 and cylinder 4 and proceeds above the piston, due to the static head of said water. The impure water is heated when chamber 21 and pipe 3^a are again supplied with steam, thus leaving a scale deposit which tends to clog up the draining orifice 63.

To prevent this drawback, mantle 77 is provided with an annular recess 78, in communication with the atmosphere by means of an orifice 79 of small section. In this manner, any water which tends to rise above the piston, at closed throttle, is directly discharged through orifice 79.

It will be seen that the above-described arrangement affords a substantial simplification over the prior constructions, due to the elimination of a receptacle, open to the atmosphere, on conduit 6, it being replaced by a simple vent pipe which serves as a safety means in case the water in vessel 70 would be heated to the boiling point by the excess of hot water returned through pipes 2 and 6.

Having now described my invention what I claim as new and desire to secure by Letters Patent is:

1. A hot water feeding arrangement for boilers comprising a source of cold water, a feed water heater, means for supplying said heater with heating steam, cold water supply means for supplying said heater with water from said source of cold water, boiler feeding means, means for connecting the intake of said feeding means, with the outlet of said heater, an overflow compartment in said heater, water discharge means for connecting said overflow compartment with the intake of said cold water supplying means, steam trap means in said water discharge means, and a vent pipe of suitable height opening into said water discharge means past said steam trap means.

2. A hot water feeding arrangement for boilers comprising a source of cold water, a feed water heater comprising a substantially closed mixing chamber, means for supplying said mixing chamber with heating steam, cold water supplying means for supplying said mixing chamber with water from said source of cold water, a substantially closed distribution chamber, a hydraulic joint between said chambers, the weight of the water column forming said joint being

adapted to be overcome by the pressure of the heating steam, whereby water and steam are caused to flow from said mixing chamber into said distributing chamber, said mixing chamber containing substantially no water, a storage compartment in said distributing chamber adapted to receive the water from said mixing chamber, boiler feeding means, means for connecting the intake of said feeding means with the outlet of said storage compartment, an overflow compartment in said distributing chamber adapted to receive the overflow from said storage compartment, water discharge means for connecting said overflow compartment with the intake of said cold water supplying means, steam trap means in said water discharge means, and a vent pipe of suitable height opening into said water discharge means, past said steam trap means.

3. In an arrangement as claimed in claim 1, a suction vessel on the intake conduit of said cold water supplying means, said water discharge means opening into said suction vessel and said vent pipe opening into said discharge means between said steam trap means and said suction vessel.

In testimony whereof I have signed my name to this specification.

SEBASTIEN OTTO ALFRED FIEDLER.
